UNITED STATES PATENT OFFICE.

JULIUS J. KARGES, OF MAYWOOD, MISSOURI.

DISPLAY DEVICE.

1,232,564.

Specification of Letters Patent. Patented July 10, 1917.

Application filed July 16, 1914. Serial No. 851,299.

To all whom it may concern:

Be it known that I, JULIUS J. KARGES, a citizen of the United States, residing at Maywood, in the county of Jackson and 5 State of Missouri, have invented certain new and useful Improvements in Display Devices, of which the following is a specification.

My invention relates to improvements in 10 display devices.

One of the objects of my invention is to provide a novel display device, such as a stand, which may be extended to a considerable height or contracted to relatively compact form, and which may be quickly and easily extended or contracted, and which will reliably support a considerable weight, when extended, without collapsing from the position to which it may be adjusted.

20 A further object of my invention is to provide a display stand with an article supporting member which may be quickly and easily adjusted to different angles, and which will be reliably retained in the position to 25 which it may be adjusted.

Other novel features of my invention are hereinafter fully described and claimed.

In the accompanying drawings, which illustrate my invention,

30 Figure 1 is a perspective view of a stand made in accordance with the principles of my invention and provided with a pivoted article supporting member shown in solid and dotted lines respectively in two positions.

Fig. 2 is an enlarged vertical sectional view of a part of the stand shown in Fig. 1.

Fig. 3 is an enlarged view, partly in vertical section and partly in elevation of the 40 frictional holding device provided in the extensible standard of the stand shown in Figs. 1 and 2.

Fig. 4 is a vertical section on the line 4—4 of Fig. 3.

45 Fig. 5 is a cross section on the line 5—5 of Fig. 4.

Fig. 6 is an enlarged view similar to Fig. 3, showing a modified form of frictional holding device.

50 Fig. 7 is a cross section on the line 7—7 of Fig. 6.

Similar reference characters designate similar parts in the different views.

1 designates a base adapted to support an extensible vertical standard comprising, 55 preferably the following described parts:—

2 designates a vertical outer tubular member having secured therein, preferably rigidly, an inner tube 3, located at the upper end of the member 2, and provided with 60 a longitudinal notch 4, preferably arcuate, and forming a slot at its middle portion which extends through the wall of the tube 3.

Mounted in the slot and notch 4 is a bow 65 spring 5 adapted to have its ends bear against the inner side of the outer member 2, and having its convex side adapted to rest against the wall of the inner tube. The bow spring 5 has its central portion adapted 70 to extend inwardly beyond the inner wall of the inner tube, and is adapted to bear yieldingly against the periphery of a support 6 comprising a vertical rod which is 75 slidable in the inner tube 3, and which at its upper end pivotally supports a flat tablet or article supporting member 7, which is provided with two staples 8, in its under side, which are pivotal supports for a rectangular eye 9 formed in the upper end of 80 the rod 6.

For supporting the article supporting member 7 in such positions as it may be adjusted to, it is provided in its under side with a staple 10 to which is pivoted by an 85 eye 11 the upper end of a rod 12 which is slidably mounted in an inner tube 13, which is secured in the upper end of an outer member or tube 14, the lower end of which is pivoted to a horizontal bolt 15, which extends 90 through the two arms of a U shaped clamping member 16, and is adapted to draw said arms toward each other so that they may tightly clamp the rod 6. By loosening the bolt 15, the clamping member 16, may be 95 vertically adjusted on the rod 6.

The inner tube 13 is provided in its outer periphery with an arcuate notch 17, the middle portion of which extends through the wall of the tube, and has mounted in it 100 a bow spring 18, the convex side of which adjacent to its ends is adapted to rest upon the outer wall of the inner tube 13, and which is adapted to have its middle portion bear against the rod 12, said middle portion, 105 when the rod 12 is removed from the tube

13, being adapted to extend inwardly beyond the inner wall of the inner tube 13. The ends of the bow spring 18 are adapted to bear against the inner wall of the outer tube 14, when the rod 12 is inserted in the tube 13.

To raise the article supporting member 7, it is but necessary to pull the rod 6 upwardly in the inner tube 3 to the desired position, after which it will be releasably and reliably held by means of the bow spring 5.

The member 7 may then be swung to the desired angle on the rod 6, in which position it will be releasably and reliably held by the bow spring 18 bearing against the rod 12 and outer member 14, said rod and member, together with the clamping member 16 forming an extensible brace for supporting the member 7.

20 In assembling the device, the bow spring 5 is first inserted in the notch 4, after which the inner member 3 is slipped into the outer member 2 to the position shown in Fig. 2, in which position the spring will be retained 25 in place by the outer member, which may be secured permanently to the inner member in any suitable manner, as by soldering, or by being tightly fitted therein.

In the form of my invention shown in Figs. 30 6 and 7, the parts are constructed similarly to the corresponding parts in the other form of my invention, excepting that in the notches 4, of which two are provided respectively in opposite sides of an inner tube 3', there are 35 respectively mounted upon said tube two friction plates 19 adapted to respectively bear against opposite sides of the rod 6. Two arcuate or bow springs 5' are respectively located in the notches 4 and have their convex sides respectively bearing against the plates 19, the ends of said springs bearing 40 against the inner wall of the outer tubular member 2 in which the tube 3' is secured.

In the form shown in Figs. 6 and 7, the 45 springs 5' normally force the plates 19 against the rod 6, thereby reliably holding it in the position to which it may be adjusted.

While I have illustrated my invention as 50 applied to a stand, such as is adapted to support hat or shoe samples, it is obvious that my improvement is adapted to be used

for various other purposes than herein mentioned.

I do not limit my invention to the structure shown and described, as modifications, within the scope of the appended claims, may be made without departing from the spirit of my invention.

Having thus described my invention, what 60 I claim and desire to secure by Letters Patent, is:—

1. In a display device, a tubular outer member, an inner tube secured therein and provided with a slot, a spring mounted in 65 said slot at the outer side of and supported by the outer wall of the inner tube and adapted to bear against the outer member and having a portion extending through the slot beyond the inner wall of the inner 70 tube, and a member longitudinally slidable in the inner tube and adapted to bear against and compress said spring.

2. In a display device, a tubular outer member, an inner tube secured therein and 75 provided in its outer periphery with a notch having its middle portion extending through the adjacent wall of the inner tube, a bow spring having its convex side adjacent to its ends bearing against the notched portion of the inner tube and extending through said notch beyond the inner wall of the inner tube, and retained in said notch by the outer member, and a member longitudinally 80 slidable in the inner tube and adapted 85 to bear against and compress said spring.

3. In a display device, a support, an article supporting member pivoted thereto, an outer tubular member pivoted to said support, an inner tube secured in said outer 90 member and provided with a slot, a member pivoted to said article supporting member and slidable in said inner tube, and a spring located in said slot and having a portion extending through said slot and bearing 95 against said slidable member.

In testimony whereof I have signed my name to this specification in presence of two subscribing witnesses.

JULIUS J. KARGES.
